US00D972589S

(12) United States Design Patent (10) Patent No.: US D972,589 S
Stewart (45) Date of Patent: * Dec. 13, 2022

(54) PORTION OF A DISPLAY SCREEN WITH A GRAPHICAL USER INTERFACE

(71) Applicant: Hoffmann-La Roche Inc., Little Falls, NJ (US)

(72) Inventor: Kevin Adam Stewart, Dundee (GB)

(73) Assignee: Hoffmann-La Roche Inc., Little Falls, NJ (US)

() Term: 15 Years

(21) Appl. No.: 29/831,061

(22) Filed: Mar. 17, 2022

Related U.S. Application Data

(62) Division of application No. 29/725,783, filed on Feb. 27, 2020, now Pat. No. Des. 949,890.
